No. 692,809.

Patented Feb. 4, 1902.

J. L. WHITE.

GRATE.

(Application filed Sept. 9, 1897.)

(No Model.)

UNITED STATES PATENT OFFICE.

JAMES L. WHITE, OF WEST SUPERIOR, WISCONSIN, ASSIGNOR TO J. L. WHITE FURNACE COMPANY, OF MILWAUKEE, WISCONSIN, A CORPORATION OF WISCONSIN.

GRATE.

SPECIFICATION forming part of Letters Patent No. 692,809, dated February 4, 1902.

Application filed September 9, 1897. Serial No. 651,139. (No model.)

To all whom it may concern:

Be it known that I, JAMES LUTHER WHITE, a citizen of the United States, residing at West Superior, in the county of Douglas and State of Wisconsin, have invented certain new and useful Improvements in Grates; and I do hereby declare the following to be a full, clear, and exact description of the invention, which will enable others skilled in the art to which it appertains to make and use the same.

My invention relates to various new and useful improvements in grates, and particularly to rocking grates. The essential novelty in the invention is the provision of a grate which shall be capable of use in connection with forced and natural drafts.

The invention relates to a grate composed of a series of hollow bars, each having a slotted upper part and a hinged lower portion and with means for forcing a blast of air through the bars. The hinged portions are so arranged that they may be closed by means of movable lugs carried upon a slidable bar. The lower face of each hinged section is sector-shaped, so that it may be at all times in engagement with its operating-lug during the rocking movement. With my improved grate-bars, therefore, the furnace will be capable of consuming sawdust and similar fuels which require a forced draft and also for consuming wood, coke, coal, and similar fuels with which a natural draft alone is required.

My improved invention further relates to details of construction for simultaneously opening and closing the removable portions of the grate-bars and for simultaneously rocking the said grate-bars irrespective of the positions of said removable portions.

In the accompanying drawings I illustrate a grate employing my present improvements.

Having reference to the drawings, Figure 1 is an isometric view, partially in section, illustrating a portion of a grate, one of the grate-bars being entirely removed, another being cut in section, and a third having a portion of its top removed; Fig. 2, a cross-section through the grate-bars, illustrating the preferred form of same and showing a convenient way for operating the hinged sections when used; and Fig. 3, a detail perspective

view of a portion of one of the grate-bars shown in Figs. 1 and 2.

In all of the above views corresponding parts are represented by the same numerals of reference.

55

1 and 2 represent the side walls of a furnace, and 3 represents the bridge-wall thereof.

4 is the front of the furnace, constructed, as heretofore, of an iron plate or plates. This particular plate is shown as being provided with two openings or doors at its lower portion to provide for the natural draft when used and which may be closed by means of suitable covers, if desired.

60

Built within the bridge-wall 3 is the main air-duct 5, made in separable sections, each formed with an overhanging lip 6, which will engage with the edge of the adjacent section. The sections of the air-duct are rectangular, as shown. This allows them to squarely rest upon the supporting-base of brickwork and at the same time will give a level bed for that portion of the rear wall above the air-duct. The face of the duct within the furnace is perpendicular to engage with the rear extremity of the grate-bar 13 and is provided with a circular opening 7. The bar snugly fits against the inner face of the air-duct and is supported within the opening 7. It is advantageous to make the air-duct 5 in sections, 70 as in that way the air-duct can be made to accommodate furnaces of different sizes, as will be understood.

75

8 8 represent two piers or supports within the furnace, upon which is carried the metal bridge 9, preferably cast in one piece. The said bridge is provided with bearing-openings 10 therein for supporting the pins 11, cast with the front of each grate-bar 12. The rear ends of the grate-bars are provided with tubular necks 13, which engage with the openings 7 in the air-duct, whereby the grate-bars may be rocked, as will be presently explained.

90

Each grate-bar 12 preferably comprises a main portion 13, consisting of two longitudinally-parallel but vertically-converging walls, (see Fig. 2,) each sustained at its forward end by the front 14 and at intermediate points by braces 15, a removable slotted or slotted top 16, and a hinged flap or door 17. I pre- 100

fer to employ removable slotted tops 16, for the reason that when said tops become burned out they may be removed and replaced by new ones, thereby obviating the necessity of removing the entire grate-bar in that event.

In order to further lessen the loss by the burning out of the tops, I prefer to make them in several sections for each grate-bar, as shown in Fig. 1. The openings or slits in the top 16 are sufficiently small to prevent the passage of fuel through the same, and their size will be determined by experience. The said tops may be removably secured in place in any suitable way; but I prefer to employ 15 inturned lugs 18 thereon, which engage with lips 19, cast upon the upper and outer edges of the main portions 13 of the grate-bars, as will be understood.

As stated, each grate-bar is preferably provided with a hinged flap or door 17, opening downward; but there may be employed two flaps or doors hinged at both sides, as will be understood.

20 is a rod or bar carried in suitable supports 21, (see Fig. 1,) preferably at the back of the furnace, said bar being provided with vertical lugs 22, having cut-away portions 23, the latter engaging the flaps or doors 17 and normally maintaining them in their closed 25 positions, as shown in dotted lines, Fig. 2. When, however, the rod or bar 20 is moved to the position shown in full lines in said figure, the flaps or doors 17 will be allowed to open by their weight. The doors or flaps 17 30 are preferably trough-shaped. Their lower faces are curved to the shape of a sector of a circle the center of which is the center of the support 11. The cut-away portions 23 of the lugs 22 are designed to fit the flaps 17 irrespective of the position of the grate-bars. If 35 two flaps are used, hinges are provided on each side, the joint between the two flaps being in the middle, and in this case, as well as where a single flap is employed, the lower face is curved, so that all portions of said 40 lower face are equidistant from the point of suspension of the grate-bar. In order that the bar or rod 20 may be thus operated, it may be provided with a rack 24 thereon, with 45 which a pinion 25 engages, said pinion being mounted on a shaft 26, having a squared front end 27 protruding through the front wall 4 of the furnace and which may be engaged by a wrench 28, so as to be rotated, as will be 50 understood.

In order that the grates may be rocked, I preferably provide each of said grates with a downwardly-extending arm 29 at its forward end, said arms being connected together by a 55 rod 30.

31 is a rock-shaft mounted in bearings in the bridge 9 and front wall 4 and provided with a downwardly-extending arm 32, which

connects with the rod 30 by a link 33. The rock-shaft 31 is provided with a squared front portion, with which the wrench 28 may also engage, as shown in Fig. 1, and by means of which the said rock-shaft may be oscillated back and forth to rock the grates to one side or the other, as will be understood. The bottoms of the flaps 17 being sector-shaped and the cut-away portions 23 being made to fit, the grate-bars may be rocked, if desired, with the flaps 17 closed, the bottoms of the latter engaging with the cut-away portions 23 through the entire extent of movement of the grate-bars.

In order to make the combustion more perfect, I prefer to extend up from the air-duct 5 at each side an auxiliary duct 34, mounted 80 in the side walls 1 and 2 and which are each provided with openings 35, communicating with passages 36, formed in said side walls, by means of which air blast or jets will be directed into the combustion-chamber a sufficient distance above the grates to result in the consumption of any gases which may be generated therein. For a similar purpose I provide a plurality of air-pipes 37, likewise connecting with the air-duct 5 and which are 85 mounted in the bridge-wall 3, as will be understood.

Having now described my invention, what I claim as new therein, and desire to secure by Letters Patent, is as follows:

1. An improved hollow grate-bar, suitable for forced and natural drafts, provided with pivotal supports at the extremities thereof, whereby it may be rocked, and with a hinged section 17, adapted to be closed when used 100 for forced drafts, and opened when used for natural drafts, the lower face of said hinged section being sector-shaped, a lug 22, with a cut-away portion 23 thereon, adapted to be brought into engagement with the lower face 105 of said hinged section for closing the same, and means for rocking said grate.

2. An improved grate, comprising a plurality of hollow grate-bars, each having a slotted upper portion and a hinged lower section, 110 the lower faces of said lower section being sector-shaped, drawn upon a center adjacent to the axis of said grate-bar, a reciprocating rod or bar mounted beneath the said grate-bars, and lugs carried by said bars for engaging with the lower faces of said hinged section, whereby the same may be closed and means for simultaneously rocking said grate-bars, substantially as described.

This specification signed and witnessed this 120 14th day of August, 1897.

JAMES L. WHITTE.
